UNITED STATES PATENT OFFICE

2,106,430

EXTINGUISHER

Joseph Humbert, Brussels, Belgium

Application March 23, 1934, Serial No. 717,106
In Belgium and France March 27, 1933

4 Claims. (Cl. 169—11)

The invention relates to extinguishers and concerns particularly the extinguishers of the type in which an extinguishing substance under pressure, and specially carbon dioxide is used as extinguishing medium.

The extinguishers in which the outflow of the extinguishing medium is obtained by percusing a diaphragm or like thin plate member are known, and it has also been proposed to provide the extinguishers of the type comprising an extinguishing substance under pressure with a distributing pipe or hose, but in the proposed constructions the percusing operation is not always effected in a safe and reliable manner and on the other hand the operator has to make use of both hands in performing the operations of either starting or stopping the projection.

An object of the invention is to overcome these drawbacks.

The invention mainly consists in arranging the percusing device to promote its efficiency and reliability in operation by suitably retaining the cut out portion of the diaphragm or plate member while the pressure of the extinguishing substance to be projected assists the release of the percusing member.

The invention further consists in the combination with the extinguishing apparatus of the kind aforesaid, of a valve like member mounted on the projecting pipe or hose, the arrangement being such that the operation of the extinguisher and the projection may be accomplished through the operator by means of one and the same hand, while the other hand may be used to perform other useful operations as for example the transportation of the apparatus.

A form of construction of an extinguishing apparatus in accordance with the invention will be now described, by way of example, with reference to the accompanying drawing, in which:

Fig. 1 shows in side elevation, the extinguisher and its projecting device.

Fig. 2 is a central sectional view of the percusing device.

Fig. 3 is a similar view of an alternative construction of the percusing device.

Referring to Fig. 1, there is shown at 1 a container, filled with the extinguishing substance under pressure, for example carbon dioxide, and 2 indicates the distributing pipe or hose, connected to the body 4 of the diaphragm arrangement 5.

In order to insure the projection of the extinguishing substance, the diaphragm 5 is per-

cuted by means of a plunger 6 retained in its upper position by the spring 7.

As will be seen from Fig. 2, the plunger 6 is formed with a part tubular member, bevelled at 8 and provided with an inner circular shoulder 9. 5 Preferably a corresponding shoulder is also formed on the outer surface of the plunger.

The purpose of the inner shoulder 9 is to retain the cut out portion of the diaphragm 5 when the latter is percused, to avoid any possibility of this 10 portion interfering with the flow of the extinguishing substance while forming a piston like member on which acts the inner pressure to cause the plunger 6 to be quickly returned to its upper or normal position.

In this position, the outer or external shoulder corresponding to the shoulder 9 presses against the packing 10 arranged around the plunger, thus forming a tight seal during the projection.

In Fig. 3 the plunger 6 is likewise formed in 20 the shape of a cylindrical member, having a reduced lower portion the end of which is provided with a number of projections or cutting teeth 8.

At this end also the plunger is bored out a 25 certain distance, the diameter of the bore decreasing comparatively rapidly so as to retain the cut out portion of the diaphragm or plate like member at a short distance from the end of the plunger and thus forming a piston like member 30 on which the inner pressure may act to quickly return the plunger to its upper or normal position.

At the location of its enlargement, the plunger is provided with an annular shoulder 9¹ on which 35 is arranged a packing washer 10.

The plunger portion of larger diameter passes through the opening 6¹ of a cover 4¹ serving as a guide therefor and a return spring 7 is arranged between the top of the cover 4¹ and a knob 7¹ 40 screwed on the end of the plunger.

If desired the inner face of the cover 4¹, on which bears the washer 10, may be provided with concentric or other ribs.

To enable the operator to start and to stop the 45 projection by means of the hand which directs the hose 2 towards the fire, a check or plunger valve is provided on said hose towards the end thereof and controlled by means of a hand lever 13 pivoted at 14 on the valve casing, said hand lever extending parallel to the hose 2 over the handle 15.

A distributing nozzle of any suitable construction, not shown, may be connected to the outer end of the valve device.

The operation is as follows:

When it is desirable to project the extinguishing substance, for example upon a fire, the operator grips the hose by means of the handle 15 of the valve device and by means of the other hand causes the diaphragm 5 to be punctured by lowering the plunger 6.

Under such circumstances the cut out portion of the diaphragm enters the bore at the working 10 end of the plunger and in the constructional example illustrated in Fig. 2 engages the shoulder 9 of said bore. The inner pressure acting on the area of the cut out portion drives back the plunger 6, in the same direction as the force of 15 the spring 7.

The extinguishing substance then fills the pipe or hose 2 and becomes available at the distributing nozzle (not shown) upon actuation of the valve device 12.

20 To cause the extinguishing substance to be projected, the operator then presses down the hand lever 13, moving the latter towards the handle 15 by means of the hand which directs the projection hose.

25 Consequently the other hand is available to perform any useful operation such for example as the transportation of the extinguisher.

It is to be understood that the constructional 30 forms described and illustrated are merely examples and that modifications may be made therein within the limits of the invention.

I claim:

1. An extinguisher filled up with an extinguishing substance under pressure and comprising a 35 discharge head, said discharge head being provided with a discharge passage, a diaphragm, a movable puncturing plunger like member, means for moving the plunger away from the diaphragm and at the opposite side of the discharge passage 40 relative to the diaphragm, means in the form of cutting projections on said plunger to cut out a portion of said diaphragm, means within the plunger behind and near said projections to retain the cut out portion in a piston head like 45 position whereby when the diaphragm is punctured the pressure of the extinguishing substance acts on said piston head to assist driving back the plunger like member with the cut out portion therein clear of the discharge passage 50 and interference with the outflow of the extinguishing substance is avoided.

2. An extinguisher filled up with an extinguishing substance under pressure and comprising a discharge head, said discharge head being provided with a diaphragm, a movable plunger like 55

member, a guide for the plunger, said guide loosely fitting said plunger, means for normally retaining the plunger in a retracted position, a discharge passage located between the diaphragm and the plunger when in said retracted position, means in the form of cutting projections on said plunger to cut out a portion of said diaphragm, means within the plunger behind said projections and near of its operative end to retain the cut out portion in a piston head like position, an external 5 shoulder on the plunger, a seat on said guide and packing means cooperating with said shoulder and seat whereby when the diaphragm is punctured the pressure of the extinguishing substance acts on said piston head to assist driving back 10 the plunger like member with the diaphragm cut out portion therein clear of the discharge passage and prevent any interference with the outflow of the extinguishing substance and the packing means are pressed between the shoulder 15 and seat to insure fluid tightness around the plunger.

3. In an extinguisher filled with an extinguishing substance under pressure, a discharge head including a diaphragm and a discharge passage, 25 a puncturing plunger and guide means for said plunger in said head at one side of said diaphragm, means for moving the plunger away from the diaphragm and a ring of toothed-shaped projections located at the inner end of the 30 plunger for cutting out a portion of the diaphragm, said projections providing means for retaining the cut-out portion of said diaphragm on the plunger whereby such portion is carried with the plunger when said plunger is moved 35 through said diaphragm and liberated therefrom.

4. In an extinguisher filled with an extinguishing substance under pressure, a discharge head including a diaphragm and a discharge passage, a 40 movable puncturing plunger at one side of said diaphragm, means in said head for longitudinally guiding the movement of the plunger, an imperforate tubular end portion on said plunger and a plurality of pointed toothed-shaped projections distributed around the edge of said tubular end 45 portion for cutting out a portion of the diaphragm, and means positioned near the end of said tubular end portion for retaining the cut-out portion of said diaphragm within said tubular end, whereby a portion of the diaphragm is cut out and carried with the plunger when said plunger is moved through said diaphragm and retracted therefrom.

JOSEPH HUMBLET.
